Patented Mar. 26, 1918.

UNITED STATES PATENT OFFICE.

FRANK L. CROCKETT, OF NORTH UXBRIDGE, MASSACHUSETTS, ASSIGNOR TO WHITIN MACHINE WORKS, OF WHITINSVILLE, MASSACHUSETTS, A CORPORATION OF MASSACHUSETTS.

TOP COMB FOR COTTON-COMBERS.

1,260,876.

Specification of Letters Patent. Patented Mar. 26, 1918.

Application filed October 6, 1916. Serial No. 124,025.

To all whom it may concern:

Be it known that FRANK L. CROCKETT, a citizen of the United States, residing in North Uxbridge, Massachusetts, has invented the following-described Improvements in Top Combs for Cotton-Combers.

The new construction improves the facility for adjustment and decreases the cost of production of the top comb mechanism of 10 Heilmann type combers and consists in the special formation of the comb blade and the combination therewith of means for its attachment to the top comb arms and in other features hereinafter explained and more 15 particularly pointed out in the claim.

In the accompanying drawings:

Figure 1 represents a central vertical section through the top comb in position in the head of a Heilmann type comber;

20 Fig. 2 is a top plan with parts broken out; Fig. 3 a vertical section through one of the attachment means on line III—III of Fig. 2;

25 Fig. 4 is a front elevation of the comb blade disconnected from the arms and angle brackets; and

Fig. 5 a top plan of an angle bracket.

The top comb arms 1 will be understood to be carried on the usual top comb shaft 2 30 and normally supported by their abutment screws 3 resting on suitable abutments on the frame of the combing machine not shown in the drawings. The forward ends of the two arms carry the comb blade 4 holding it 35 normally in a position between the detaching rolls 5 and the nipper jaws 6, as indicated in Fig. 1, being in this position close to the path of the combing cylinder which is represented by the dotted lines 7, and being 40 adapted to be lifted and swung upwardly from this position about the axis of the shaft. The function of the top comb in its relation to these various parts requires not only that it be rigidly and firmly supported in its normal position but that it be 45 set and adjusted with extreme accuracy, as well understood by those familiar with combing.

The top comb blade is formed of a flat 50 plate, of uniform thickness and can be conveniently stamped out of sheet metal stock.

Along its lower edge it is rabbeted to receive the row of combing needles 8 soldered in the rabbet groove. Its upper part is cut away at the central portion (10) forming two upward arms 11 near each end and the upper extremities of these arms are bent over forming attachment or adjustment lugs 9, extending rearwardly and at right angles to the upper part of the blade. The arms and 55 their lugs constitute the means of attachment of the comb blade to the angle brackets 13 by which they are secured to the inner faces of the swinging arms 1. Each arm of the comb blade 11 is provided with a vertical oblong slot to receive a clamp bolt 14 and each lug 9 is provided with an open slot in its rear edge to receive the groove of an adjustment nut 12. The latter is carried on the threaded stud 18 rising from the top 60 of the angle bracket and serves to raise and lower the position of the blade on the bracket in obvious manner. The bolt 14 is tapped into the body of the bracket below the screw stud 18 and serves to clamp the blade in its 65 adjusted position. There being a bracket of the kind described at each end of the comb blade, each is drilled transversely to the clamp bolts 4, to receive the bolt 15 by which the brackets are pivotally mounted on the 70 ends of the arms 1. Each bracket is further formed with a rearward flange 13^a having an arc-shaped slot 16 therein, by means of which the bolts 17 clamp the bracket to the arms 1 and secure the adjustment of the 75 bracket in any angular position to which it may have been moved about the axes of the bolts 15. When the blade has been adjusted on the brackets and the latter on the top comb arms, and the several bolts firmly 80 tightened, the comb construction is a rigid unit quite as suitable for practical use as the one piece and much heavier structures heretofore employed. As above stated, it is moreover less expensive in cost, and can be 85 produced with a high degree of accuracy and uniformity. The comb blade may be left flat if desired, but is preferably bent longitudinally as shown in the drawings to increase its stiffness and also to accommodate 90 the angle of the nipper jaws.

Having now described the principle of the

invention and the preferred form thereof,
what is claimed is—

A top comb construction for Heilmann
type combers comprising the combination
5 with the top comb arms of adjustable angle
brackets secured at the ends of said arms

and a sheet metal top comb blade adjustably
clamped to the forward faces of said bracket
pieces.

In testimony whereof, I have signed this 10
specification.

FRANK L. CROCKETT.
